UNITED STATES PATENT OFFICE.

ANDREW CARLSON, OF MULLEN, NEBRASKA.

CHICKEN-BEHEADER.

1,271,016.

Specification of Letters Patent.

Patented July 2, 1918.

Application filed August 13, 1917. Serial No. 185,983.

To all whom it may concern:

Be it known that I, ANDREW CARLSON, a citizen of the United States, and residing at Mullen, in the county of Hooker and State 5 of Nebraska, have invented certain new and useful Improvements in Chicken-Beheaders, of which the following is a specification.

This invention relates to guillotines, and it more particularly relates to a device for beheading chickens.

10 One of the objects of this invention is to provide a simple, effective and comparatively inexpensive device whereby the heads of chickens and other fowls may be instantaneously and completely severed.

15 Another object of the invention is to provide a device of this character which may be attached to a fence post, or other support to which it may remain as a fixture.

20 Another object of the invention is to provide a device of this character which is strong and durable.

25 Other objects and advantages may become apparent to persons who read the following detailed description in connection with the accompanying drawings, in which—

Figure 1 is a side elevation view, and

Fig. 2 is a vertical sectional view, the section being taken along the line 2—2 of 30 Fig. 1.

Referring to these drawings in detail, in which similar reference characters correspond with similar parts throughout the several views, the support 10 may consist of 35 a post, the corner of an out-house, or any vertical surface. A bar or strap 11 of sheet metal is slightly offset at 12 and provided with apertures through which bolts or other fastening elements 13 extend, the latter also 40 extending into the support 10 so as to rigidly unite the support and the bar 11. A pair of blades 14 are mounted in parallel and spaced relation upon the supporting bar 11, rivets 15 being employed for securing the blades,

45 while washers 16 are placed around the respective rivets 15, and effect the spacing of the blades 14. Each blade 14 is provided with an upwardly extending element 17, and these elements coöperate with one another 50 for guiding a vertically movable blade 18.

The elements 17 also constitute a stop against which the neck of the chicken may rest for preventing removal of the same from the space between the knives 14 and 55 18 when the latter is raised. One of the elements 17 also coöperates with a handle bar

19 for limiting downward movement of the knife 18.

The handle bar 19 is preferably formed of a rectilinear strip or bar of metal, except 60 that one end portion is bent at 20 so as to provide a space between its end and the adjacent end of the knife 18. The supporting bar 11 is embraced in the space between the ends of the knife 18 and handle bar 19, 65 while a rivet or pivot 21 extends through aligned apertures in the members 11, 18 and 19. This arrangement of the pivot 21 and its adjuncts insures a strong pivotal connection of these elements while accurately 70 guiding the knife 18. Rivets 22 are employed for rigidly uniting the knife 18 and handle bar 19. The handle bar is provided with a ball or weight 23 on its free end, for a purpose which will hereinafter become ap- 75 parent.

In operating this device, the lever or handle bar 19 is first swung upon the pivot until the gap between the blades 14 and 18 is sufficient to allow the head of the chicken to 80 pass through this gap, and when its head has passed entirely through the gap, the lever 19 is swung downward with a quick movement, so that the momentum of the weight coöperates with the lever and knives 85 for instantly severing the chicken's neck.

From the foregoing, it will be seen that I have provided a device of this character which is thoroughly practical and efficient for the purpose intended, and which, it is 90 believed, will become very popular and meet with great commercial success.

Although I have described this embodiment of my invention, minutely, it is to be understood that my invention is not limited 95 to these exact details of construction and arrangements of parts, but my invention may be limited only by the scope of the appended claims.

What I claim as my invention is:

1. A device of the character specified, comprising a fixed blade supported at one end in horizontal position and provided at its opposite end with a vertically extending element forming a guide and double stop, a 105 pivoted blade disposed against a side of the fixed blade and the vertically extending element thereof, and a handle bar pivoted in line with the pivoted blade and secured to the upper edge thereof and disposed in the 110 plane of the fixed blade and engageable with the top of the vertical element thereof.

2. A device of the character specified, comprising a bar, a fixed blade secured at one end to the bar and having an integral guide and stop element projecting from its outer end in the plane of the blade, a second blade disposed against a side of the fixed blade and the projecting element thereof, a handle-bar secured to a side of the second blade with the upper edge thereof and engageable with the top of the projecting ele-

ment of the fixed blade, and pivot means constituting the handle-bar and second blade to each other and to the before mentioned bar.

In testimony whereof I affix my signature 15 in presence of two witnesses.

ANDREW CARLSON.
